UNITED STATES PATENT OFFICE.

THOMAS V. ALLIS, OF PITTSBURGH, PENNSYLVANIA; HANNORA E. ALLIS ADMINISTRATRIX OF SAID THOMAS V. ALLIS, DECEASED.

SHEET AND TIN MILL FURNACE.

1,318,948.

Specification of Letters Patent.

Patented Oct. 14, 1919.

Application filed April 8, 1916. Serial No. 89,964.

To all whom it may concern:

Be it known that I, THOMAS V. ALLIS, a citizen of the United States of America, residing at Pittsburgh, in the county of Allegheny and State of Pennsylvania, have invented certain new and useful Improvements in Sheet and Tin Mill Furnaces, of which the following is a specification.

In the art of manufacturing sheets and tin plate the metal bars are rolled down in pairs in a heated state, to sheets of the desired gage. It is customary to reheat and double the metal one or more times intermediate the bar and finished stage. The heating of the bars and the intermediate re-heating is effected in separate furnaces as the temperature of the bar or "pair" furnace is not suitable for the intermediate re-heating.

My improvements consist in a superior arrangement of a continuous "pair" heating furnace, a "sheet" or intermediate re-heating furnace, and independent fire boxes for each furnace, all contained in a unitary structure, whereby valuable floor space is economized, and the operation of the various parts aforesaid is facilitated.

In the accompanying drawings forming part of this specification,

Figure 1 is a sectional plan view of the unitary structure.

Fig. 2 is an elevation partly in section on line II—II of Fig. 1.

Figs. 3 and 4 are sectional elevations on planes indicated respectively by the lines III—III, and IV—IV of Fig. 1.

In the practice of my invention the chamber 1 for heating the bars, and the chamber 2 for the intermediate reheating are formed in a unitary structure, but are separated, the one from the other by a partition wall 3.

It is preferred to employ for heating the bars a continuous type of furnace in which the bars after being admitted through the charging door 4, are fed through the heating chamber by being pushed forward from the rear end to a point accessible through the discharge door 4.

The "sheet" furnace is provided with an opening and door 5 on the same side of the unitary structure as the discharge door for the bar furnace as shown in Fig. 1, and the partially reduced sheets are charged into and removed from the furnace through this door 5.

As the partially reduced sheets will occupy considerably more space than the sheet or tin bars, the chamber 2 is made substantially wider than the chamber 1 employed for heating the bars. 60

But as the bars are charged into the bar furnace cold, the chamber 1 is made substantially longer than the chamber 2, thereby providing a sufficient length of travel of the bars to insure their being properly heated. 65 The chamber 1 is made of greater width toward its discharge end, than at its charging end to provide space for manipulating the bars.

The greater width of chamber 2 permits 70 the placing of the fire boxes or combustion chambers 6, and 7, in the rear of said chamber and the greater length of the chamber 1 permits of the fire boxes being made of sufficient depth, without extending the vertical 75 plane of the rear end of the chamber 1. The fire box 6 which is arranged on the opposite side of the partition wall 3 from the chamber 1, is connected to said chamber adjacent to its rear end by an opening 8 Fig. 3, 80 through partition 3, the portion 9 of such partition below the opening forming the bridge wall over which the products of combustion pass into the rear end of the chamber 1. For convenience of illustration the 85 opening 8 in the partition 3 is shown by dotted lines in Fig. 1. Products of combustion escape from chamber 1 through a flue 10 Fig. 3, located adjacent to the front or discharge end of the chamber, said flue being connected to a passage 11, which in turn 90 communicates with a stack 11a.

The products of combustion flow from the fire box 7 over the bridge wall 12 into the chamber 2, and escape therefrom through the vertical ports 13, 13, located on opposite sides of the chamber, adjacent to the front end thereof, and thence to a stack (not shown). As the fire box 7 is located to one side of the chamber 2, the side wall of the opening 14, above the bridge wall is cut away at 15 to permit products of combustion to flow laterally toward the inner side wall of the chamber 2. For convenience of illustration the opening 14 is 100 shown by dotted lines in Fig. 1. Coal is fed to the fire boxes through openings 16, 17, though other forms of fuel may be employed by adapting the fire boxes thereto. It is characteristic of my improvement that 110

the fire boxes are located closely adjacent to each other, thus facilitating the handling of fuel, especially when coal is used, and this desirable result is attained without interfering with charging bars into the rear end of the chamber 1. The bars being charged into the bar furnace at its rear end, the space between the front of said furnace and the train of rolls used in reducing the bars, 10 is left free for the manipulation of the metal in such process of reduction.

I claim herein as my invention:

1. In a unitary structure, the combination of a continuous pair heating furnace and a sheet heating furnace, the pair furnace provided with receiving and discharging doors at opposite ends, a fire box located at one side of its receiving end and partially in the rear of the sheet furnace, the sheet furnace provided with a fire box located wholly at its rear and adjacent to the pair furnace fire box.
2. In a unitary structure, the combination of a continuous pair heating furnace and a sheet heating furnace, the pair furnace provided with receiving and discharging doors at opposite ends, a fire box located at one side of its receiving end and partially in the rear of the sheet furnace, the sheet furnace provided with a fire box located wholly at its rear and adjacent to the pair furnace fire box, the pair furnace being less in width at its charging end than toward its discharging end.
3. In a unitary structure, the combination of a continuous pair heating furnace and a sheet heating furnace, the pair furnace provided with receiving and discharging doors at opposite ends, the pair furnace being less in width at its charging end than toward its discharging end, an independent fire box

connected to the pair furnace through an opening in its side wall at its charging end and a second independent fire box connected to the sheet furnace through an opening in its rear wall, said fire boxes being located in the rear of the sheet furnace, at one side of the pair furnace and adjacent to each other.

4. In a unitary structure, the combination of two heating chambers provided at their front ends with doors for the removal of the heated articles, and independent fire boxes for said chambers arranged in the rear and within planes coincident with the side walls 55 of one of said chambers.

5. In a unitary structure, the combination of two heating chambers, provided at their front ends with doors for the removal of the heated articles, and one of the chambers 60 provided with a charging opening at its rear end, and independent fire boxes for said chambers arranged in the rear end of one of the chambers, and at one side of the rear portion of the other chamber.

6. In a unitary structure, the combination of two heating chambers, provided at their front ends with doors for the removal of the heated articles, and one of the chambers provided with a charging opening at its 70 rear end; a fire box connected to the chamber having front and rear openings through an opening in the side wall of said chamber, and a second fire box connected to the other chamber through an opening in its rear wall. 75

In testimony whereof, I hereby affix my signature, in the presence of two witnesses.

THOMAS V. ALLIS.
